UNITED STATES PATENT OFFICE.

SAMUEL R. PARRY, OF ROCHESTER, NEW YORK.

LINING-MACHINE.

1,242,970.

Specification of Letters Patent. Patented Oct. 16, 1917.

Application filed June 29, 1912. Serial No. 706,708.

To all whom it may concern:

Be it known that I, SAMUEL R. PARRY, a citizen of the United States, residing at Rochester, in the county of Monroe and State of New York, have invented certain new and useful Improvements in Lining-Machines, of which the following is a specification.

The object of this invention is to produce a machine for lining or covering cardboard, strawboard, chipboard, etc., such as is ordinarily used for making paper boxes, picture mounts, calendar mounts, etc.

Another object of this invention is to produce a machine that will take the lining or covering paper continuously from a roll, apply the paste or glue thereto and feed it into contact with the sheets of cardboard under pressure and heat.

Another object of this invention is to provide mechanism for cutting the continuous web of lining or covering paper at the end of each sheet of cardboard.

Another object of this invention is to provide mechanism for feeding continuously the consecutive sheets of cardboard to the machine, leaving only a small interval between them.

Another object of this invention is to provide a series of pairs of pressing rolls, the upper roll of each pair being mounted so as to be readily thrown into and out of contact with its companion roll.

Another object of my invention is to provide mechanism for applying smoothly and evenly a film or coating of paste or glue to the web of winding paper as it passes through the machine.

Another object of my invention is to provide a suitable mount for the roll of paper by which a uniform and accurate tension may be placed upon the web of paper as it is fed through the machine.

Another object of my invention is to provide mechanism to facilitate putting the roll of paper in place on the machine.

Another object of my invention is to provide means for preventing the paper from coming in contact with the pasting roll when the upper rolls of the pairs are thrown out of position.

In the accompanying drawings, Figure 1 is a top plan view of the machine.

Fig. 2 is a side elevation of the machine viewed from the right hand side of Fig. 1.

Fig. 3 is a side elevation of the machine viewed from the left hand side of Fig. 1.

Fig. 4 is a section on the line 4^x—4^x of Fig. 1.

Fig. 5 is a detail view of the mechanism 60 for regulating the feed of paste on the coating roller.

Fig. 6 is a section through one of the heating rollers, these being the lower rollers of each pair in which they occur.

Fig. 7 is a longitudinal section through the paper roll and the support therefor.

Fig. 8 is a detail perspective view of the mechanism for cutting the paper.

Fig. 9 is a sectional elevation on the line 70 9^x—9^x of Fig. 1, showing the mechanism by which the cutting mechanism is operated.

Fig. 9^A is a sectional elevation on the line 9^{Ax}—9^{Ax} of Fig. 8.

Fig. 10 is a section on the line 10^x—10^x of 75 Fig. 9.

Fig. 11 is a detail view of the roller for stretching or smoothing the paper.

Fig. 12 is a top plan view of the mechanism for raising the paper roll.

Fig. 13 is a detail view of the last pair of rollers, partly broken away.

Fig. 14 is a horizontal section on the line 14^x—14^x of Fig. 2.

In the accompanying drawings like reference numerals refer to like parts.

In my machine is included mechanism for supporting the paper roll, mechanism for applying paste or glue to this paper roll, mechanism for feeding the paper from this 90 roll to the machine in contact with sheets of cardboard, mechanism for cutting the web of paper at the end of each sheet of cardboard, and means for driving a heating roll so that the paper and cardboard will be firmly pressed together and caused to adhere one to the other.

There is also included in the machine mechanism for separating the upper roller from the lower roller of each pair and mechanism for feeding the paper out of contact with the pasting roll operating in connection with the mechanism for separating the rollers of each pair.

The machine also includes feed regulating mechanism by which the sheets of cardboard are fed consecutively to the machine.

In the accompanying drawings reference numeral 1 indicates the framework of the machine, which consists of two uprights 110

shown in side elevation in Figs. 2 and 3 and which are firmly bolted together in any suitable manner.

At the bottom of the machine at the rear 5 end, is mounted the roll of paper 2. This roll of paper is supported on the shaft 3, which shaft carries thereon the cones 4 and 5, which cones may be either round or square and which cones engage with the 10 interior of the tube on which the paper is wound.

Mounted on the shaft 3 are the sleeves 6 and 7, each of which sleeves carries therein the set screws 8 and 9. Each of the sleeves 15 is threaded at 10 and 11, which threaded portion of the sleeve extends into a recess in the cones 4 and 5. On this threaded portion of the sleeve is mounted to turn a collar 12 and 13. The sleeves 6 and 7 are 20 clamped in place by the set screws 8 and 9, after which by turning the collars 12 and 13 the cones 5 and 4 can be forced firmly 25 into engagement with the roll so that the roll 2 and the shaft 3 and the parts interposed therebetween will all turn in unison.

Mounted on each of the frames 1 are the brackets 14 and 15, which brackets are pivotally mounted on the studs 16 and 17, these brackets being oppositely placed on the machine to each other and being similar in 30 shape symmetrically reversed to each other. Each of these brackets comprises a web 14^a and 15^a, in which webs at the bottom are placed bolts 18 and 19, which bolts engage 35 with suitable openings in the frames, by which the brackets are held in the position shown in Figs. 1 and 2. These bolts can be disengaged from the openings and the brackets can be rotated to the dotted line position 40 shown in Fig. 2. In traveling from the full line to the dotted line position, the pins 18 and 19 bear against the curved tracks 20 and 21 and engage with the stops 22 and 23 at the end thereof, by which their further 45 movement in that direction is arrested.

The shaft 3 rests in the bearing at each end thereof, one of which is shown in Fig. 12 at 24. This bearing 24 is integral with the bracket and is U-shaped and open at the 50 top, affording opportunity for the shaft to turn loosely therein.

Pivotally mounted on the brackets 14 and 15 are the jaws 25 and 26 shown in Fig. 2 and the jaws 27 and 28 shown in Figs. 3 55 and 12. Each of these jaws is pivotally mounted at the bottom on the pins 29 and 30 that are integral with the brackets. At the top each of these jaws is recessed to a half round to receive the shaft 3. These 60 jaws are drawn together by the hand wheels 31 and 32, causing them to exert pressure and friction on the shaft 3, by which the shaft 3 is retarded in its rotation. The bearings may be lined with leather or any 65 other suitable soft anti-friction material

which bears directly on the shaft and by which the friction on the shaft may be regulated.

In operation the brackets are first swung to the dotted line position shown in Fig. 2, 70 in which position the paper roll is placed in position with the shaft 3. After the paper roll has thus been secured to the brackets, the brackets are rotated to the full line position by the levers 33 and 34, in which 75 position it is locked by the pins or bolts 18 and 19, engaging the recesses in the frame provided therefor.

The machine is provided with a pasting 80 or coating mechanism by which a film of paste is applied to the paper web as it passes through the machine, and this mechanism will now be described.

Suitably mounted in the machine is the paste box 36 carried at each end on standards 37 and 38 which have racks on the side thereof which engage with pinions on each side, such as is shown at 39 in Fig. 4, both of which pinions are mounted on the same shaft, which shaft can be conveniently operated by the hand wheel 40, by which hand wheel the paste box may be placed in any desired elevation. The ratchet and pawl 41 and 42 are provided in connection with the hand wheel 40, by which the hand wheel 95 may be held in position when the desired elevation of the paste box 36 is secured.

Mounted to rotate in the frame of the machine is the coating roll 43. The paste box 36 is elevated until the paste therein comes 100 in contact with this roll. The paper 89 travels in the direction indicated by the arrow in Fig. 4 and in so traveling passes over the idle roll 44 and the paste roll 43. Between the idle roll 44 and the paste roll 105 43 is mounted the distributing roll 45 which bears against the paste roll 43 for the purpose of distributing the paste thereon. This roll is mounted at each end in bell cranks 46 and 47, shown in Figs. 2 and 3 respectively. 110 The free ends of these bell cranks are connected to the frame of the machine by the turn buckles 48 and 49, by which the contact between the distributing roller 45 and the pasting roller 43 may be regulated, so that 115 the amount of paste carried by the paste roller 43 may be varied at will.

Between the distributing roller 45 and the paste roller 43 is carried the rod 50, which rod is mounted in the free end of the arms 120 51 and 52, by which it may be raised and lowered, as will presently be described.

Mounted on the frame of the machine is a scraper 53 which bears against the paste roller 43 and keeps the roller clean. Also 125 mounted in the frame of the machine are the rollers 54, 55 and 56, against which the upper surface passes idly as it passes toward the pairs of pressing rollers. The roller 56 is shown in Fig. 11, and is shown therein 130

as provided with helical ridges 57 thereon, by which the paper is stretched toward the edges and the wrinkles therein are smoothed out.

5 On top of the machine are provided a series of feeding and pressing rollers, which rollers I will now describe.

At the front of the machine is provided the feed table 60, upon which the cardboard stock is placed that is to be fed to the machine. Adjacent to this feed table are the feed rollers 61 and 62, each of which rollers consists of a small shaft having at suitable intervals narrow collars placed thereon, between which narrow collars the stock is fed forward by frictional engagement. The upper roller rests loosely in the bearings by which it is supported. As shown in Fig. 1, five collars are placed upon each of the upper and lower rollers, this number or even more being desirable for heavy cardboard. In working on light cardboard the number of collars on the upper roll may be decreased and the collars may be moved laterally on the shaft so that each of the remaining collars will only partially engage with the collars on the lower roll, in this way decreasing the frictional engagement between the rollers and the cardboard, which engagement in any case is preferably just enough to secure proper feeding of the cardboard.

Mounted in the frame of the machine is the square bar 63 having the spring pressing fingers 64 thereon which bear loosely against the cardboard stock as it is fed forward. The bearing for the bar 63 is split at 65 so that the bar 63 may be rotated to any angular position and clamped therein. This is for the purpose of adjusting it to different thicknesses of cardboard.

Next in order are the rollers 67 and 68, the roll 68 being unyieldingly mounted in the frame of the machine, and the roll 67 being yieldingly mounted in the bell crank levers 69 and 70, which levers are pivoted to brackets that are integral with the frame of the machine, the lever 69 being shown in Fig. 9 pivoted at 71 on the bracket 72. Each of these brackets is provided with an arm 50 that projects inwardly, in which a set screw 73 is mounted which bears against the bell crank 69, by which the angular adjustment of it is secured. A bracket 74 is also provided rigid with the frame of the machine, 55 to which a spring 75 is connected, which spring in turn is connected to the bell crank 69, by which the roller 67 is yieldingly held in engagement with the roller 68. Similar mountings for the roller 67 are provided on both sides of the machine.

The roller 68 is provided with a series of collars, preferably four or more in number, all of which are clamped to the shaft. The roller 67 is provided with two collars 76 and 77 loosely mounted thereon with a tripping

device or feed regulator rigid with the shaft between them. A detail of this arrangement is shown in Fig. 10, in which the shaft or roller 67 is shown provided with the sleeve 78 having a flange on one end thereof and 70 having a reduced end with a shoulder at the other end thereof. On the reduced end is clamped the collar 79, which collar is preferably set up close against the shoulder. The collar 77 is thus mounted to rotate loosely 75 on the sleeve 78 and is held in place by the flange at one end of the sleeve and the collar 79 at the other end. The sleeve 78 and collar 79 are of course mounted to rotate with the roller 67 and not independent thereof. Between the flanges on the sleeves 78, as shown in Fig. 10, the tripping device 80 is supported. This tripping device consists of a knife blade 80^A that is set eccentrically in the flanges of the sleeve 78 and is normally held 80 in the position shown in Fig. 9, in which position it bears against the sheet of cardboard as it is fed through the machine.

On the knife is provided shoulders 81, as shown in Figs. 1 and 9. When one sheet of 90 cardboard is passing under the knife with the knife resting loosely thereon, the next sheet of cardboard advances, partly overlapping the preceding sheet, and is deflected upward by the knife so that it comes into 95 contact with the shoulders 81, by which its further forward movement is arrested, as shown in Fig. 9. As soon as the preceding sheet of cardboard has passed the knife the knife drops down, being urged on thereto 100 by the pressure of the succeeding sheet of cardboard which is urged forward by the rollers 61 and 62. The knife and the roller 67 by which it is carried are rotated by the advancing sheet of cardboard until the knife 105 has passed clear around the circle, the initial part of the rotation being secured by the direct contact between the advancing sheet of cardboard and the knife, and the remainder of the rotation being secured by the frictional engagement between the collars 76 and 77 and the sheet of cardboard. The roller 67 is out of balance, the flange on the sleeve 78 being cut away at 82 in order to contribute to this result, so that the knife will drop 110 down quickly and follow the end of the sheet of cardboard around, being impelled thereto by the frictional engagement between the loose collars 76 and 77 and the roller 67 by which the knife is carried, so that the sheet 115 of cardboard as it advances, being driven by the rollers 61 and 62, causes the roller 67 to rotate and bring the knife once more into engagement therewith. This knife does not have any cutting action and is called a knife 120 simply because of its shape which is preferred on account of convenience, the thin edge of it being easily passed between the edges of consecutive sheets.

On the end of the roller 67 is provided a 130

stud 83, which stud as the roller rotates operates on the lever 84 pivoted at 85 on the frame of the machine. The opposite end of this lever is hook shaped, as shown at 86, for 5 a purpose that will now be described.

After leaving the rollers 67 and 68 the cardboard passes between the rollers 87 and 88 which are solid rollers, the bottom roller being positively driven and the upper roller 10 being driven by the contact of the cardboard which is fed between the two rollers. The paper web 89 from the roller 2 passes up over the roller 88 and first comes into contact with the cardboard between the rollers 87 and 88. Beyond these rollers the cardboard and the paper pass on together.

Next after these rollers are arranged the rollers 90 and 91, by which the paper is cut at the end of each sheet of cardboard, the 20 roller which is above comprising a hollow tube having the longitudinal opening 92 therein, on the front side of which is the flange 93. The roll 91 is made preferably as a casting, having three longitudinal ribs 25 thereon spaced 120 degrees apart between centers, which ribs are connected at regular short intervals by circular flanges, the details of which are shown in Fig. 8. Fastened to one of the longitudinal ribs is the cutting 30 knife 94, which cutting knife engages with the longitudinal recess 92 in the roller 90 for the purpose of cutting the paper at the end of each sheet of cardboard, or for the purpose of separating consecutive sheets of cardboard that are otherwise connected together 35 by the continuous web of paper. The operation of these rolls with their cutting knife is timed to occur at the end of each sheet of cardboard. This result is secured as follows:

The rolls 90 and 91 are spaced from the knife 80^a of the tripping device 80 by a distance which is sufficient to allow the cam 83 to trip the lever 84 and secure the rotation 45 of the rollers 90 and 91 from the position shown in Fig. 9 to the position shown in Fig. 9^a during the interval elapsing from the time that the end of the sheet of cardboard passes the tripping device 80 until it reaches 50 the position of the knife 94 in Fig. 9^a. The stud or cam 83 is set upon the roller 67 so as to have a delayed action on the lever 84 and this in connection with the distance through which the knife 94 must travel from 55 the position shown in Fig. 9 to that shown in Fig. 9^a is sufficient to cause the knife to act on the paper at the end of the sheet of cardboard so as to separate the adjacent edges of the cardboard from each other, 60 which edges are separated from each other approximately by the thickness of the knife of the tripping device 80.

The roller 91 is driven by the friction clutch 95, the outer member of which is 65 positively driven by a chain gearing which

will be hereinafter described, the inner member of which is driven by frictional contact with the outer member except when it is arrested by the hook shaped end 86 of the lever 84. The hook shaped end 86 of the 70 lever 84 is normally held down in engagement with the disk 96 by means of the tension spring 97. The disk 96 has a shoulder 98 thereon, by which the hook shaped end 86 of the lever 84 can engage it to arrest 75 the motion of the roller 91 upon the completion of each revolution thereof, so that the roller 91 will rotate but once for each sheet of cardboard that passes thereover, or but once for each time that the tripping device 80 80 operates through the roll 67 to trip the lever 84. The cutting effect is increased by mounting the roller 90 on bearings that are slightly eccentric thereto, the eccentricity being so located as to crowd the rollers together when they are in the position shown in Fig. 9^a.

Next after the cutting rollers are the heating and pressing rollers which are arranged in pairs and any desired number of pairs 90 of them may be provided in the machine, five of such pairs however being shown in the arrangement illustrated in Fig. 4. These rollers are numbered 99, 100, 101, 102, 103, 104, 105, 106, 107 and 108. The upper 95 rollers of each pair are solid and are allowed to press loosely against the sheet of cardboard as it is fed through, no springs being used to increase the pressing effect, the weight of the rollers being sufficient for this 100 purpose, although springs may be used if so desired. Each of the lower rollers is hollow and is provided with a burner 109 therein, as shown in Fig. 6, in which gas may be burned for the purpose of heating 105 the rollers. If desired the rollers may be heated by steam instead.

Each of the upper rollers is carried in a stirrup 110 at each end, in which it is mounted to rotate. Each of these stirrups 110 has a cross arm at the top thereof in which adjusting screws 111 are provided by which the stirrup may be raised or lowered. By this adjustment each of the upper rollers may be kept normally slightly out of contact with the roller below it, leaving a small amount of clearance between them, which clearance will be varied according to the thickness of the stock which is being operated on by the machine, so that the roller in 115 each case will not bear too heavily upon the cardboard but will bear thereon just enough to secure the desired result.

On each side of the machine at the top is mounted two slide bars 112 and 113 125 which bars have cams 114 therein which are normally located immediately under the shafts of the rollers and as the bars are slid longitudinally the rollers are lifted by the cams so as to be completely out of engage- 130

ment with the cardboard that is passing through the machine and by which the feed of the cardboard will be arrested. By this device the feed of the rollers may be stopped without stopping the machine and any material which may have adhered to the rollers may be easily removed therefrom. These bars are operated from the lever 114^a which is pivoted on the frame of the machine 5 at 115. At the free end thereof a link 116 is connected which is in turn connected to the crank 117. The crank 117 is a double ended crank and at the opposite end thereof has connected thereto a link 118 which link 10 is in turn connected to the crank 119, which crank is keyed to the shaft 120. On this shaft 120 at each end are keyed the forked arms 121 and 122, which forked arms engage with anti-friction rolls on the bars 113 and 20 112, by which the bars are reciprocated in unison upon the operation of the lever 114^a.

Keyed to the shaft 120 is the crank 123 (see at the right of Fig. 1) to which in turn is connected the link 124, to which in turn 25 is connected the crank 125 keyed to the shaft 126, on which shaft are arms 51 and 52 such as are shown in Figs. 2, 3 and 4 between which is carried the bar 50 over which the paper travels. When the lever 114^a is operated to raise the upper rollers, the bar 50 is also raised to lift the web of paper 89 out of contact with the paste roll 43, so that 30 paste will no longer be applied to the paper. When the rolls are lifted by the bars 112 and 35 113 the feed of the machine will be stopped as follows:

The sheet of cardboard to which the web of paper is partly pasted by the roll 88 will be held back by the web of paper 89, 40 the friction of the lower rollers being insufficient to pull it forward against this resistance. The web of paper will also be out of contact with the paste roller 43 which can continue to rotate idly. As soon as the 45 lever 114^a is thrown in the reverse direction, the upper rollers are lowered in to contact with the cardboard that must be fed through, the paper web 89 is lowered into contact with the paste roller 43 and the feed 50 of the material and the operation of the machine is resumed.

On each of the rollers 99 to 108 inclusive a scraping knife 130 is provided, arms 131 being provided on each side of the machine 55 for each pair of rollers on which the scraping knives 130 are pivotally mounted so as to bear against the roller which revolves against them. Under the rollers 99 to 108 inclusive, I place the pan 132 which keeps 60 the dirt which may fall down from the rollers from getting to the paper web or to the paste box.

The various parts of the machine are driven as follows: Mounted to rotate in the 65 frame of the machine is the shaft 135 on

which is keyed the pulley 136 and the pinion 137. This pinion in turn meshes with the pinion 138 mounted on a jack shaft, to which is also keyed integral therewith the pinion 139 shown in Fig. 2, which pinion 70 in turn meshes with the pinion 140 which is mounted to rotate loosely on the shaft 135 which forms a bearing therefor. The pinion 139 also meshes with the pinion 141 on the paste roll 43 and the pinion 141 in 75 turn meshes with the pinion 142 on the distributing roll 45. The pinion 140 meshes with the pinions 143 and 144, by which the rollers 102 and 104 respectively are driven. Meshing with the pinion 143 is the idle pinion 143^a which in turn meshes with the pinion 145 on the roller 100, by which the roller 100 is driven. Integral with the pinion 145 is the sprocket gear 146 which drives a sprocket chain 147 which in turn drives 80 a sprocket gear 148, which in turn drives a friction clutch 95 through which the cutting roll 91 is driven. The cutting roll at the far end is provided with a pinion 149 which meshes with a pinion 150 on the roll 90 90, by which the rolls 90 and 91 are driven in unison. The pinion 145 also meshes with the pinion 151, which in turn meshes with the pinion 152, which pinion drives the roll 88. On the shaft of the roll 88 is mounted the 95 sprocket wheel 153 which drives a sprocket chain 154, which chain engages with the sprocket wheel 155 on the roll 68 and the sprocket wheel 156 loosely mounted on the roll 62, the motion of this sprocket wheel 100 being communicated to the roll through a friction clutch 157, the parts of which are yieldingly held together by the spring 158 which is compressed by the hand wheel 159 which has a threaded engagement with the 105 end of the roll by which the spring may be compressed and the friction of the clutch may be regulated at will. The pinion 144 meshes with the idle pinion 160 which in turn meshes with the pinion 161 on the 110 roller 106. The pinion 161 in turn meshes with the pinion 162, which in turn meshes with the pinion 163 on the roller 108. The rollers 99, 101, 103 and 105 may be driven positively by gears from the lower rollers 115 of the pairs to which they belong, or they may be driven solely by frictional contact with the cardboard stock passing through the machine.

The roller 108 is positively driven by the 120 pinion 163. The roller 108 has keyed thereto the pinion 164 which in turn meshes with a pinion 165 mounted to rotate loosely upon the upper roller 107. A friction clutch 166 consisting of a washer and nut is interposed 125 between the pinion 165 and the shaft of the roller 107, which clutch may be adjusted to secure any desired torque upon the roller 108.

A feed table 60 is provided at the front 130

end of the machine, on which is provided a gage 170 which is adjustable for the purpose of securing the correct feed of the sheets of cardboard through the machine.

5 Having thus described my invention, what I claim as new and patentable is as follows:

1. In a lining machine the combination of a series of pressing rollers arranged in pairs, feeding mechanism adapted to feed sheets 10 of cardboard suitably spaced apart between said pressing rollers and separate overlapping sheets, mechanism for applying a pasted web of paper to said sheets of cardboard, and means operating to cut said web 15 of paper at the end of each sheet of cardboard.

2. In a lining machine the combination of a series of pressing rollers arranged in pairs, feeding mechanism adapted to feed sheets of 20 cardboard suitably spaced apart between said pressing rollers and separate overlapping sheets, mechanism for applying a pasted web of paper to said sheets of cardboard, and means operating to cut said web 25 of paper at the end of each sheet of cardboard, said mechanism being set in operation by each succeeding sheet of cardboard.

3. In a lining machine the combination of 30 a pair of feed regulating rolls for regulating the passage of sheets of cardboard, one of said rolls being intermittent in its operation and turning a single revolution for each sheet of cardboard passing said roll, means 35 on said roll for arresting the rotation thereof during the passage of the intermediate portion of the sheet of cardboard, and a pair of pressing rolls between which the sheets of cardboard pass from said feed 40 regulating rolls, one of said pressing rolls being adapted to guide a web of paper passing thereover into contact with said cardboard.

4. In a lining machine the combination of 45 a frame, a series of pressing rolls mounted to rotate therein and arranged in pairs, the upper rolls being driven by frictional contact from the lower rolls, and means for simultaneously lifting the upper rolls out 50 of driving contact with said lower rolls, said upper rolls remaining idle while in said elevated position.

5. In a lining machine the combination of 55 a frame, a series of pressing rolls mounted to rotate therein and arranged in pairs, the upper rolls being driven by frictional contact from the lower rolls, means for simultaneously lifting the upper rolls out of driving contact with said lower rolls, said upper 60 rolls remaining idle while in said elevated position, a paste roll in said machine, said

paste and pressing rolls being adapted to receive a web of paper to pass over said paste roll and between said pairs of rolls, and means for lifting said web of paper out 65 of contact with said paste roll, said means being operated upon the separation of said pairs of rolls.

6. In a lining machine the combination of a frame, a pair of pressing rolls mounted 70 therein, a paste roll mounted therein, said paste and pressing rolls being adapted to receive a paper web to pass over said paste roll and between said pressing rolls, said pressing rolls being driven to draw said web 75 of paper through the machine, and means for simultaneously separating said rolls and for lifting the paper web out of contact with the paste roll, whereby the feeding and pasting of the paper web is stopped.

7. In a lining machine the combination of a frame, a series of rolls mounted therein arranged in pairs, the upper roll of each pair being driven by frictional contact with the lower roll, shafts projecting from each 80 end of the upper rolls of each pair, a cam bar on each side of said machine passing under said shafts, said bars being movable endwise to raise or lower said rolls, a paste roll in said machine, said paste roll being 85 adapted to receive a web of paper passing thereover, a bar mounted adjacent to said paste roll and adapted when moved to lift the paper out of contact with said paste roll, and means for simultaneously moving said 90 bars to separate the rollers and the bar for lifting the paper out of contact with the paste roll.

8. In a lining machine the combination of a frame, means for feeding a pasted web of 100 paper through said machine, means for applying sheets of cardboard suitably spaced apart to said web, and separate overlapping sheets and means operated by each sheet of cardboard for cutting the web at the end 105 of each sheet of cardboard.

9. In a lining machine the combination of a frame, a series of pressing rollers mounted in said frame in pairs, scrapers bearing against certain ones of said pressing rolls, a paste box and roll mounted below said pressing rolls, and a plate placed below said pressing rolls and above said paste roll to arrest thereon any matter dropping from 110 said pressing rolls.

In testimony whereof I affix my signature in presence of two witnesses.

SAMUEL R. PARRY.
